UNITED STATES PATENT OFFICE

WALTER SCHULTZE, OF M.-GLADBACH, GERMANY

TRAVELING CLEANING DEVICE FOR THE STRETCHING MECHANISM OR DELIVERY MECHANISM OF SPINNING OR TWISTING MACHINES

Application filed September 22, 1931, Serial No. 564,442, and in Germany October 1, 1930.

This invention relates to a traveling cleaning device for stretching or delivering mechanisms of spinning or twisting machines, in which a cleaning brush situated with its axle 5 at an angle to the axle of the upper cylinder, automatically glides over the stretching or delivering mechanism.

- It is known to arrange a conical cleaning brush on two upper cylinders to clean the stretching mechanism cylinders and to guide this cleaning cylinder by a frame surrounding the same and resting on the upper cylinder. In order to prevent the frame from dropping out it extends in curved-shape 15 around the rear upper cylinder and in order to prevent the cleaning cylinder from dropping out of the frame, the frame is provided with two angle supports, on which the journals of the cleaning brush slide.
- 20 It is also known to make such a cleaning brush in double conical shape and allow the same to rest with one cone on three cylinders so that it receives an inclined position and consequently slides longitudinally over the cylinders of the stretching mechanism.

The known cleaning devices can however not be employed on the delivery mechanism of a two-cylinder spinning machine and on drawing stretching mechanisms.

- 25 This invention has for its object to produce a suitable cleaning device for such spinning machines. With this object in view a conical or cylindrical cleaning brush is, according to the invention, arranged on the front upper cylinder at an angle to its axis and mounted in a frame shiftable longitudinally on rear guides, for example on the rear upper cylinder or on the rear thread guide. To enable this arrangement to be also employed on already existing stretching and delivering mechanisms, without altering the same, the frame, if guided on the rear upper cylinder, is slightly bent, but, in order to prevent it from dropping out, is provided 30 at the rear with a special counterweight. In order to be able to clean the middle drawing upper cylinder, a special cleaning brush may at the same time be arranged on the frame. If, however a cylindrical cleaning brush is chosen, it is mounted in a forked element,

oscillatable through 180° in the rear guide element, so that it can be adjusted to the most suitable position, according to the direction in which it is to automatically travel. The guide element or frame, in the case of 55 two-cylinder carriage spinning machines, slides over the known bow-shaped thread or slab guides and for this purpose is made in inverted V-shape.

If it were desired to mount the frame or 60 the forked element of the cleaning brush, for example on a continuous guide rod, in the case of two-cylinder carriage spinning machines, this would not be possible, because it is necessary to insert the slab between the 65 forked thread or slab guides about every two hours. However, as already mentioned, it is desired to enable the new cleaning device to be employed on existing arrangements without alteration.

70 Two embodiments of the invention are illustrated by way of example in the accompanying drawings, in which:

Fig. 1 shows in side elevation the employment of a conical cleaning brush with a four-cylinder stretching mechanism,

75 Fig. 2 is a front elevation of Fig. 1,

Fig. 3 is an end view, seen from the right of Fig. 4,

Fig. 4 is a front elevation, showing the employment of a cylindrical cleaning brush with a two-cylinder carriage spinning mechanism and

80 Fig. 5 is a top plan view of Fig. 4.

The cleaning device consists of a frame 1, 85 in which the cleaning brush 2 is journaled and which is moved by the cleaning cylinder over the stretching cylinders in axial direction thereto. 3, 4, 5 and 6 are the stretching cylinders in a four-cylinder stretching mechanism. The stretching cylinders are mounted in the cylinder support 7, fixed on the cylinder bank 8. The frame 1 is provided with runners 9, 10 with which it slides on the rear stretching cylinder 6. These runners must 90 be at least so long that they bear on two juxtaposed cylinders 6. Their ends are preferably bent upwards, in order to enable an easy transition from one cylinder to the other. In order to prevent the frame from dropping 95 100

off the cylinder 6, that is, to ensure a reliable bearing, one of the runners is provided with a counterweight 13.

A cylindrical brush 14 is mounted in the frame 1 and receives its drive from the inclined cleaning brush 2, for example through the intermediary of a cord or belt drive 15, 16. This brush serves for cleaning not only the cleaning brush 2, but also the upper cylinders 5 and 6. The material, which the brush 14 takes from the cleaning brush and the two upper cylinders 5 and 6, is collected in an upwardly foldable comb 18, movably mounted in a frame 17, from which comb the material is easily removed, when the cleaning device arrives at the end of the machine.

One of the arms carrying the weight 13 may be provided with a brush 19, by means of which the upper portion of the carriage 20 can be cleaned. The material taken up by the brush 19 is held in a piece of card cloth 21. A removable cover 22, lined for example with plush on the side directed towards the upper cylinder 6, may be arranged on the two runners 9 and 10 of the cleaning device for the purpose of also removing dust.

The free end of the axle 14a of the cylindrical brush 14 may be provided with a wheel shaped brush 25, by means of which a further portion of the carriage 23 and the screws mounted therein can be cleaned, whereas the drawing cylinder 4 is kept clean by a brush 26 adjustable in height.

Finally one side portion 1a of the frame 1 may be provided with a resilient wiper 28, for the purpose of subsequently cleaning the leather-lagged stretching mechanism cylinders 3. By means of this wiper the upper portion of the weight hook 29 will also be simultaneously cleaned.

When the stretching mechanism and the cleaning device are in operation, the latter moves in the direction of the arrow α (Fig. 2); it is raised at the end of the machine from the two upper cylinders 3 and 6 and placed on the other side of the machine on the stretching cylinders, after which it moves in the opposite direction, and on reaching the end of the stretching cylinders, is again placed on the upper cylinders and thus continually circulates.

In the form of construction illustrated in Figs. 3 to 5, the cleaning brush 2 is cylindrical and is mounted in bearing slots 30 of a fork 31, and bears on the upper cylinder 3 of the stretching mechanism. Fork 31 has a pin 33 mounted thereon extending nearly perpendicularly to the axis of cylindrical brush 2. Pin 33 may be changed in position in a guiding frame 32 by 180° by removing the fork 31 from the machine and re-inserting pin 33 with the brush and supporting structure in reversed position. On bows 34 arranged in a common bar 35, the element 32, bent in inverted V-shape, slides like a rider, the ends of

this element being slightly bent over outwardly, in order to ensure a reliable transition from one bow 34 to the next without jamming. The pin 33, mounted in the guiding element 32 approximately perpendicularly to the axle of the upper cylinder 3, is bent at an angle so that the fork 31 extends with the brush 2 at an angle to the axle of the upper cylinders. When the cleaning device, consisting of the parts 2, 31, 32 and 33, reaches the end of the machine, the automatic return of the cleaning device is started by swinging the fork 31 with the cleaning brush 2 out of the position shown in Fig. 5, into that indicated by the dot-dash line $x-y$.

It is evident that such a cleaning device can be employed not only on spinning and twisting machines for working cotton, but also on machines for any other fibrous material.

I claim:

1. A traveling cleaning device for a textile machine embodying a plurality of cooperating rotating cylinders comprising a frame longitudinally shiftable along said cylinders, a cleaning brush bearing upon only one of said cylinders at an inclination with respect to the axis of said cylinder rotatably mounted in said frame, whereby the rotation imparted by said one cylinder to said brush actuates said frame in a longitudinal direction, a second cleaning brush actuated by said first brush cooperating with other cylinders of said machine, and guide means for said frame.

2. A traveling cleaning device for a textile machine embodying a plurality of cooperating rotating cylinders comprising a frame longitudinally shiftable along said cylinders, a cleaning brush bearing upon only one of said cylinders at an inclination with respect to the axis of said cylinder rotatably mounted in said frame, whereby the rotation imparted by said one cylinder to said brush actuates said frame in a longitudinal direction, a second cleaning brush actuated by said first brush cooperating with other cylinders of said machine, a comb mounted on said frame cooperating with said brushes, and guide means for said frame.

3. A traveling cleaning device for a textile machine embodying a plurality of cooperating rotating cylinders comprising a frame longitudinally shiftable along said cylinders, a cleaning brush bearing upon only one of said cylinders at an inclination with respect to the axis of said cylinder rotatably mounted in said frame, whereby the rotation imparted by said one cylinder to said brush actuates said frame in a longitudinal direction, a second cleaning brush actuated by said first brush cooperating with other cylinders of said machine, auxiliary brushes mounted on said frame for cleaning parts of said machine, and guide means for said frame.

4. A traveling cleaning device for a textile

machine embodying a plurality of co-operating rotating cylinders comprising a frame longitudinally shiftable along said machine, a fork element pivotally mounted in said frame non-parallelly with respect to said frame, bearings in said fork, a cleaning brush rotatably mounted on said bearings in contact with only one of said cylinders at an inclination with respect to the axis of said cylinder, whereby the rotation imparted by said one cylinder to said brush actuates said frame in one longitudinal direction at one position of said fork, and in the reverse direction at the position of said fork displaced 180° from said first position, and guide means for said frame.

The foregoing specification signed at Cologne, Germany this 11th day of September, 1931.
